UNITED STATES PATENT OFFICE.

CARRIE D. DUDLEY, OF CHICAGO, ILLINOIS.

DESIGN FOR A CIGARETTE TRAY.

Application filed August 31, 1922. Serial No. 3,601. Term of patent 3½ years.

To all whom it may concern:

Be it known that I, CARRIE D. DUDLEY, a citizen of the United States, residing at Chicago, in the county of Cook and State of Illinois, have invented a new, original, and ornamental Design for Cigarette Trays, of which the following is a specification, reference being had to the accompanying drawings, forming part thereof.

Fig. 1 is a perspective view, viewing the design from a side; and Fig. 2 is a perspective view, viewing the

I claim:

CARRIE D. DUDLEY.
